(57) **CLAIM**

The ornamental design for a lid for a water bottle, as shown and described.

DESCRIPTION

FIG. 1 is a perspective view of a lid for a water bottle with a water spout in a closed position showing our new design; FIG. 2 is a cross-sectional view showing a section taken along line 2-2 of FIG. 7;

FIG. 3 is a front view thereof;

FIG. 4 is a back view thereof;

FIG. 5 is an enlarged left side view thereof;

FIG. 6 is an enlarged right side view thereof;

FIG. 7 is a top view thereof;

FIG. 8 is a bottom view thereof;

FIG. 9 is a perspective view of the lid for a water bottle with the water spout in an opened position;

FIG. 10 is a cross section view showing a section taken along line 10-10 of FIG. 15;

FIG. 11 is a front view thereof;

FIG. 12 is a rear view thereof;

FIG. 13 is an enlarged left side view thereof;

FIG. 14 an enlarged right side view thereof;

FIG. 15 is a top view thereof; and,

FIG. 16 is a bottom view thereof.

The broken lines in the drawings depict portions of the lid for a water bottle that form no part of the claimed design.
